US00D615070S

(12) **United States Design Patent**
Andre et al.

(10) **Patent No.:** US D615,070 S
(45) **Date of Patent:** ** May 4, 2010

(54) **EAR PIECE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/339,483**

(22) Filed: **Jun. 30, 2009**

Related U.S. Application Data

(63) Continuation of application No. 29/321,427, filed on Jul. 16, 2008, now Pat. No. Des. 595,270.

English Translation of a search report for Taiwan Patent Application No. 096303170, dated Mar. 25, 2008.

U.S. Appl. No. 29/270,881, titled "Ear Piece", filed Jan. 5, 2007.

Primary Examiner—Paula Greene

(74) *Attorney, Agent, or Firm*—Sterne, Kessler, Goldstein & Fox P.L.L.C.

(57) **CLAIM**

The ornamental design for an ear piece, as shown and described.

DESCRIPTION

FIG. 1 is a front perspective view of an ear piece showing our new design.

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines in the Figures show portions of the ear piece that form no part of the claimed design.
